UNITED STATES PATENT OFFICE.

HOMER D. WILLIAMS, WILLIAM AHLEN, AND AMBROSE N. DIEHL, OF DUQUESNE,
PENNSYLVANIA.

METHOD OF CHARGING BLAST-FURNACES.

No. 905,125.

Specification of Letters Patent.

Patented Nov. 24, 1908.

Application filed October 10, 1907. Serial No. 396,754.

To all whom it may concern:

Be it known that we, HOMER D. WILLIAMS,
WILLIAM AHLEN, and AMBROSE N. DIEHL,
all of Duquesne, Allegheny county, and
State of Pennsylvania, have invented a new
and useful Method of Charging Blast-Furnaces,
of which the following is a full, clear,
and exact description, reference being had
to the accompanying drawings, forming
part of this specification, in which—

Figure 1 is a sectional side elevation of
one form of apparatus as it is applied for
use at the bottom or foot of the inclined
track or skip-hoist on which materials
charged into the blast furnace are hoisted
to the top of the furnace; Fig. 2 is a sec-
tional plan view on the line II—II of Fig. 1;
Fig. 3 is a sectional side elevation of an-
other form of apparatus adapted for use in
carrying out our improved method as it is
applied for use to the foot of the inclined
track leading to the top of the blast-furnace;
Fig. 4 is a plan view of Fig. 3; Fig. 5 is a
25 detail sectional plan view, on a larger scale,
showing mechanism by which the buckets
and bucket-supports are rotated on the con-
veyer forming part of the apparatus shown
in Figs. 3 and 4.

Our invention relates to the charging of
stock into blast furnaces, and it is designed
to overcome the difficulties incident to poor
distribution of the different sizes and grades
of materials in the furnace. This irregular
distribution in the furnace of the materials
35 forming the furnace burden results from
part of the materials being in lump form
and other parts being in finer or smaller
sizes or form, the consequence being that
with ordinary charging the coarse lump
40 materials will gather at one side and the
finer materials at the opposite side of the
furnace. The ascending gases will rise
through that portion of the furnace con-
taining the coarse lumpy materials, causing
45 frequent slips and explosions to occur in
the furnace, which result in damage to the
furnace and expensive delays in the opera-
tion of such furnaces.

Heretofore, various distributing devices
50 have been placed at the top of the furnace,
forming part of the hopper feed mechanism
of the furnace top. This method of distri-
bution complicates the top work of the fur-
nace and adds the apparatus at a point

where it is subjected to heat and is diffi- 55
cult of access. Such mechanism is also sub-
ject to disarrangement through slips or ex-
plosions in the furnace.

Our invention is designed to overcome
these difficulties, and it consists in distribut- 60
ing the charge before it is taken to the top
charging apparatus of the furnace. Our in-
vention, therefore, consists broadly in dis-
tributing the charges at or before the time
when they enter the carrier in which they 65
are taken to the top of the furnace. It also
consists in distributing the charge and de-
positing such charge in a bottom discharge
carrier, so that the distributed charge in the
carrier will drop into the furnace hopper in 70
a distributed condition.

In the drawings, referring to Figs. 1 and
2, 2 represents the foot of the inclined track
on which the materials charged into the
blast furnace are hoisted to the top of the 75
furnace, and 3 represents the rails forming
the track on which the scale-car or larry
runs in conveying the materials from the
stock-bins into position to be discharged into
the rotary hopper 4, which is mounted below 80
the track-rails 3. Bottom-discharge stock-
carriers or buckets 5, in which the materials
are carried on the inclined track 2 to the
furnace-top, are removably mounted upon
cars 6, these cars being arranged to run upon 85
the circular track, formed by the rails 7, in
transferring the carriers or buckets 5 be-
tween the rotary hopper 4, where they are
filled, and the point below the inclined track
2 at which the buckets are in position to be 90
engaged by the trolley hook 8 on the trolley
9 and be lifted on the inclined track 2 to the
top of the furnace. The cars 6 are secured
together by means of connecting plates 10,
so as to enable the cars to be moved together 95
upon the track-rails 7 by the driving motors
11, although instead of each car 6 being pro-
vided with a separate motor 11, as shown,
one large motor may be employed to drive
all of the cars when desired. 100

The hopper 4 is mounted beneath the scale-
car track-rails 3 upon the rollers or wheels
12, which in turn are mounted upon the
hopper track 13, and the hopper 4 is rotated
by means of the hopper driving motor 14, 105
which is connected by the slow-down gearing
15 with the bevel wheel 16 on the out-
side of the hopper 4. The hopper is pro-

vided with swinging bottom-discharge doors 17, these doors being provided with suitable operating mechanism by which they are opened and closed in discharging materials into the buckets 5, at the will of the operator.

In Figs. 3, 4 and 5 of the drawings, another form of apparatus is shown, which is adapted to be used in carrying out our invention, in which 2^a represents the inclined track leading to the top of the furnace, and 3^a the rails forming the track upon which the scale-car 18 runs in delivering materials from the stock-bins. The stock-bins are arranged to discharge materials through the spouts or chutes 19 into the scale-car 18. It not being necessary to weigh the coke forming part of the materials charged into the furnace, after the coke is placed in the coke-bins, these bins are located so as to discharge 20 through the spouts or chutes 20 direct into the charging-buckets 5^a, although the coke may be transferred from the coke bins to the buckets 5^a in the same manner as the other materials forming the furnace burden. The bottom-discharge buckets 5^a are removably placed upon bucket supports 21 on the upper section 22^a of the conveyer 22, which is located so as to transfer the buckets 5^a between the point below the scale-bar track- 25 rails 3^a, at which the buckets are loaded, to that beneath the inclined track 2^a, at which the buckets are removed from and are replaced on the conveyer by the trolley-hook 8^a of the trolley 9^a on the inclined track 2^a. The upper conveyer section 22^a is provided 30 with track-wheels 23, and the lower section 22^b with track wheels 24, the wheels 24 being mounted upon the circular track formed by the rails 25, and the wheels 23 for the top 35 section 22^a being arranged to run upon suitable track-surfaces provided on the top surface of the lower conveyer section 22^b. A central shaft 26 is provided to keep the upper and lower conveyer sections in place 40 while they are being rotated and the conveyer-sections 22^a, 22^b are driven by means of the motor 27, this motor being connected by slow-down gearing 28 through the intermediate gears 29 and 30 on the vertical shaft 45 31 with the spur-gears 32 and 33 on the periphery of the conveyer sections 22^a and 22^b. The gears 32 and 33 are of different diameters so as to cause the upper section 22^a of the conveyer to turn at a different speed 50 from that of the lower conveyer section 22^b when they are driven by the motor 27.

Part of the bucket supports 21 are secured to vertical shafts 34 by which they are caused to rotate, each on its own axis, while 55 the conveyer 22 is moved in transferring the buckets between positions in which these buckets are filled and at which the buckets are engaged by the trolley-hook 8^a to be hoisted upon the inclined tracks 2^a. The 60 bucket supports 21 are supported on the

anti-friction rollers 35 which in turn are supported upon suitable circular track-surfaces on the top face of the upper conveyer section 22^a. The lower end of the shafts 34 are provided with spur-pinions 36, which mesh with and are turned by the teeth 37 in the oscillating segmental gears 37, shown in Fig. 5. The segmental gears 37 are pivotally mounted upon the pins 38, which are secured to the upper conveyer section 22^a, 70 and intermediate of the length of the segmental gears are pins 39, each having an anti-friction roller 40, these pins and rollers projecting downwardly into one or the other of the two annular grooves or slots 41 or 42, 80 which are provided in the top surface of the lower conveyer section 22^b.

In the operation of charging by our improved method with the apparatus shown in Figs. 1 and 2, the materials are loaded into the scale-car 18 and are carried by the car on the track rails 3 into position to be discharged into the hopper 4; and the buckets 5 are then successively filled with the materials in the hopper. The hopper 4 may be 90 constantly rotated while the materials are being discharged into the buckets, or may remain stationary while one bucket 5 is filled and then be rotated before filling the next bucket, so as to bring the rectangular opening formed in opening the doors 12 on the hopper into a different vertical plane with respect to the position occupied by them in filling the previous bucket, in this way changing the distribution of the coarse 100 and fine materials in each bucket with respect to the distribution in the other bucket and finally, the distribution in the furnace of one charge with the others. As each bucket is filled, the next empty bucket 5 is 105 brought into position below the hopper 4 to be filled, and the filled buckets are moved on the ears 6 one step nearer the position at which they are removed from the cars and are carried on the inclined track 2 to the top 110 of the furnace. On reaching the top of the furnace the bucket is emptied into the furnace hopper, and the empty bucket is then returned to the car 6, in readiness to be again filled when it again reaches the charging position beneath the hopper 4. 115

In carrying out our improved method by means of the apparatus shown in Figs. 3, 4 and 5, the rotary hopper 4^a is dispensed with, and the buckets 5^a are filled direct by the scale-car 18. In this case part of the buckets 5^a are rotated, each upon its own axis, as the buckets are carried between the charging point below the scale-car and the position in which they are engaged by the trolley-hook 8^a to be lifted to the furnace top and be emptied. It not being necessary to uniformly distribute the coarse and fine parts of the charges of coke, the coke buckets 5^a are not arranged to rotate on the con- 130

veyer, although all of the buckets 5^a may be arranged to revolve, each upon its own vertical axis, if so desired.

As the conveyer revolves in carrying the 5 buckets, the upper section 22^a rotates at a different speed from that of the lower section 22^b, and by means of this difference in the speeds the projecting pins 39 extending downwardly into the recesses 41 and 42 in 10 the top surface of the lower section 22^b of the conveyer travel in and out in following the irregular contour of the recesses 41 and 15 42 and causes the segmental gears 37 to oscillate upon their pivot pins and through the pinions rotate the bucket support 21 and the bucket 5^a upon the support. The annular grooves are arranged so as to bring the buckets and the handle by which they are lifted always in the right position to be 20 engaged by the trolley-hook 8^a when the buckets reach the position below the inclined track 2^a, in which they are lifted from the conveyer by the trolley-hook, and are arranged to bring each of the rotatable buckets 25 5^a into a different position when below the scale-car 18 from that occupied by it during the previous operation, and also that occupied by the previous bucket supports 21 and the buckets upon them. Each of the 30 rotatable buckets has eleven different positions below the scale-car; and the positions occupied by the buckets being different, the stock is always deposited in such manner as to be delivered in position to be hoisted on 35 the inclined track 2^a, in twenty-two different positions relatively to each other. This results in a very uniform distribution of the coarse relative to the fine materials in the furnace, as the buckets occupy the same relative position while being emptied only after 40 a large number of charges have been put into the furnace.

The operations of removing and replacing the buckets upon the conveyer and of hoisting the buckets and emptying them into the furnace with the apparatus shown in Figs. 3, 4 and 5 are identical with those used with the apparatus shown in Figs. 1 and 2, and need not again be described.

50 The advantages of our invention are many, and will be apparent to those skilled in the art. The distribution of the coarse and fine materials is done at the base of the furnace; where the result is under the ob-

servation of the operator. We believe ourselves to be the first to provide a method of charging in which the distribution is effected at the bottom of the blast furnace, and we intend to cover the same broadly.

Many variations may be made in the top 55 charging mechanism of the furnace, and in the method of or means for distributing the charges either before they enter the carrier, or before they are fed into the carrier, without departing from our invention.

65

We claim:—

1. The method of charging blast furnaces, consisting in uniformly distributing the coarse and fine materials forming each charge, carrying the distributed charges to 70 the top of the furnace, and depositing them in an annular sheet in the top feed mechanism of said furnace; substantially as described.

2. The method of charging blast furnaces, 75 consisting in uniformly distributing the coarse and fine materials forming each charge, carrying the distributed charge in a bottom-discharge bucket to the top of the furnace, opening the bottom-discharge and 80 annularly spreading the charges as they descend into the hopper of the furnace; substantially as described.

3. The method of charging blast furnaces, 85 consisting in distributing the charges, uniformly mixing the coarse and fine materials forming each charge carrying the distributed charge in a bottom-discharge carrier to the top of the furnace, and dropping it through the carrier into the top feed mechanism of 90 the furnace; substantially as described.

4. The method of charging blast furnaces, 95 consisting in distributing the charge and uniformly mixing the coarse and fine materials forming the charge, depositing the distributed charge in a bottom discharge carrier, moving the carrier to the top of the furnace, and dropping the distributed charge into the furnace-hopper; substantially as 100 described.

In testimony whereof, we have hereunto set our hands.

HOMER D. WILLIAMS.

WILLIAM AHLEN.

A. N. DIEHL.
